DESIGN FOR A TORCHÈRE BOWL OR SIMILAR ARTICLE

Joseph T. Sheerer, Greensburg, Pa., assignor to Victory Glass, Inc., Jeannette, Pa., a corporation of Pennsylvania

Application January 4, 1940, Serial No. 89,292

Term of patent 3½ years

To all whom it may concern:

Be it known that I, Joseph T. Sheerer, a citizen of the United States, residing at Greensburg, Pennsylvania, have invented a new, original, and ornamental Design for a Torchère Bowl or Similar Article, of which the following is a specification, reference being had to the accompanying drawing, forming part thereof.

In the drawing:

The raised portions on the exterior of the bowl also appear on the interior thereof, in the reverse sense.

I claim:

The ornamental design for a torchère bowl or similar article, substantially as shown and described.

JOSEPH T. SHEERER.
